UNITED STATES PATENT OFFICE

WILLIAM SCHNELL, OF DETROIT, MICHIGAN, ASSIGNOR TO TERNSTEDT MANUFACTURING COMPANY, OF DETROIT, MICHIGAN, A CORPORATION OF MICHIGAN

SMOKING CASE

Application filed December 9, 1929. Serial No. 412,589.

This invention relates to a smoking case and more particularly to that type of smoking case which is adapted for use in an automotive vehicle.

This invention is concerned with that type of smoking case assembly which consists of an outer casing which is arranged to be secured to the wall of the vehicle and of an ash receiver which is adapted to set or fit into the outer casing. It is old in the art to fabricate this outer casing of three or more parts such as an integral back plate and bottom, an integral front plate and ends, and a top plate with an opening therein for receiving the ash receiver proper. The various plates making up the outer casing are usually nickel or chromium plated and consequently to avoid marring the back plate the ash receiver is inwardly spaced from the same. Heretofore this has been achieved by providing a top plate for the outer casing which has an opening for the ash receiver spaced inwardly from the edges of the top plate. It is the object of this invention to obviate the top plate and hence to present a smoking case which consists of an ash receiver and a two-piece outer casing for this receiver which holds the ash receiver in spaced relation with the back and front plates to prevent marring of the same when the receiver is being removed or replaced in this outer casing.

In the drawing:

Fig. 1 is a front elevation partly in section of the smoking case.

Fig. 2 is a section along the line 2—2.

Fig. 3 is a plan view of the case partly broken away.

Fig. 4 is a cross section of the unitary back and bottom plate.

Fig. 5 is a cross section of the front plate.

Fig. 6 is a fragmentary view of a portion of the back plate.

Fig. 7 is a fragmentary section of a modified form showing the panelled front plate and decorative insert.

Referring more particularly to the drawing it will be seen that the smoking set is made up of an outer casing generally designated 1 which is preferably of an ornamental character and an ash receiver 2 arranged to be re-

ceived within the said outer casing which serves primarily as a holder for the ash receiver. The ash receiver proper 2 is shown in the dotted lines in Figs. 1 and 2. The applicant does not claim any invention in the ash receiver 2 itself the configuration of which is amply disclosed in the figures, Fig. 1 showing a front view and Fig. 2 an end view. The outer casing 1 consists of two parts; namely, the integral back and bottom plates 4 and the integral front and end plate 5. The plates 4 and 5 are preferably metal stampings although they can be made of any other suitable material.

The front plate 5 is adapted to be secured to the unitary bottom and back plate 4. To this end the back plate 4 is provided with the openings 6 and the pressed-in abutments 7 and the front plate 5 is provided with the projecting lugs 8. To secure the front plate 5 to the rear plate 4, the lugs 8 are projected through the opening 6 and then bent over as shown in Figs. 1, 2, and 3.

The back and front plates 4 and 5 are preferably plated or otherwise suitably ornamented. Inasmuch as the outer casing which is made up of the two parts; that is, the integral back and bottom plate 4 and the integral front and end plate 5 is arranged to receive the ash receiver 2, it is evident that to permit the easy removal of the ash receiver 2 and to prevent the marring or scratching of the plating or ornamentation on the back plate that the ash receiver should be spaced from the said plate. Since the outer casing is comprised of but two pieces and the customary apertured top plate has been eliminated, the ash receiver 2 has been satisfactorily spaced from the inner face of the back and front plates by providing the front plate 5 with an inwardly projecting flange 9 which extends throughout the length of the upper edge of the front plate and by shearing in the back plate as at 10 to provide the L-shaped flange 11 which extends lengthwise of the back plate flush with the upper face 9 of the front plate. The ash receiver 2, as shown in Figs. 1 and 2, is received in the outer casing 1 and supported and removably held therein by engagement with the sheared

flange 11.

in flange 11 on the back plate 4 and the flange 9 on the front plate 5.

The sheared in flange 11 and the inwardly projecting flange 9 cooperate to obviate the necessity for the heretofore customary apertured top plate and thus permit a smoking case assembly of three parts; namely, an ash receiver proper and a two-piece outer casing comprising an integral front and end plate 10 and an integral back and bottom plate.

The outer casing is arranged to be secured to a suitable support, such as the wall of the vehicle, and to this end is the back plate provided with an inverted key-hole slot 14 and 15 an apertured struck-out lug 15 each of which are arranged to receive suitable attaching means such as a screw.

Instead of using the one-piece front plate 5 I can use the panelled front plate 20 which 20 has the panel openings 21. The panel front plate 20 is arranged to receive a suitable panel insert 22 which may be grained or otherwise ornamented for decorative purposes.

As shown in Figs. 1 and 2 the back of the 25 ash receiver 2 has sheared therein the spring members 23 which yieldingly engage the flange 11 on the back plate 4 to hold the ash receiver in the outer casing and to serve as anti-rattlers.

30 What I claim is:

1. A smoking case for an automotive vehicle, or the like, comprising in combination a stamped two-piece outer casing arranged to receive an ash receiver, said outer casing comprising a unitary back and bottom plate and a unitary front and end plate having a flange along the upper edge, the said back plate having an integral struck-out projecting portion cooperating with said flange for positioning the said ash receiver in spaced relation with the front and back plates, the said struck-out projecting portion being positioned between the top and bottom edges of the back plate.

2. A smoking case for an automotive vehicle, or the like, comprising in combination a two-piece outer casing arranged to receive an ash receiver, said outer casing comprising a stamped unitary back and bottom plate and a stamped unitary front and end plate having a flange along the upper edge, the said back plate having a formed-in flange portion extending transversely thereof and arranged to cooperate with said front and end plate flange for positioning the said ash receiver in spaced relation with the front and back plates, said flange being positioned flush with the upper edges of the front and end plates.

3. A smoking case for an automotive vehicle, or the like, comprising in combination a two-piece outer casing arranged to receive an ash receiver, said outer casing comprising a stamped unitary back and bottom plate and a stamped unitary front and end plate, the said front plate having an inwardly projecting flange and the back plate having a

struck-in flange extending between the side edges of the back plate and arranged to cooperate with the flange of the front plate to position the ash receiver in spaced relation with the front and rear plates.

4. A stamped sheet metal smoking case for an automotive vehicle or the like, comprising in combination an integral stamped metal portion forming a bottom and back plate, another stamped metal portion forming the end and front plates and having a flange along the upper edge, the end plate portions having lugs arranged to interengage the back plate portions, the said two stamped metal portions forming an outer casing adapted to receive an ash receptacle, the back plate having struck-in therefrom and transversely thereof, a flange extending between the two end plates, the said flange extending from end plate to end plate and being adapted to cooperate with the flange along the upper edge of the end and front plates to receive an ash receptacle and hold the same in spaced relation with the back plate.

In testimony whereof I affix my signature. 90
WILLIAM SCHINELL.
